UNITED STATES PATENT OFFICE.

JOSEPH O. CADIEUX, OF MERIDEN, CONNECTICUT, ASSIGNOR TO THE CONNECTICUT TELEPHONE AND ELECTRIC COMPANY, OF MERIDEN, CONNECTICUT, A CORPORATION OF CONNECTICUT.

RESETTING-CIRCUIT FOR ANNUNCIATORS.

1,081,266.

Specification of Letters Patent.

Patented Dec. 9, 1913.

Application filed November 7, 1912. Serial No. 729,953.

To all whom it may concern:

Be it known that I, JOSEPH O. CADIEUX, a citizen of the United States, residing at Meriden, New Haven county, and State of Connecticut, have invented certain new and useful Improvements in Resetting-Circuits for Annunciators, of which the following is a full, clear, and exact description.

This invention relates to electric annunciators employing visual indicators and a call bell or other sound device, and is more especially designed to provide means for resetting any one or more of the indicators which have been moved from normal position by a "call," this resetting operation being effected with a minimum expenditure of current. These and other advantages will be described in detail in the accompanying specification and are illustrated in the accompanying drawing forming part thereof and illustrating diagrammatically the application of my invention to a three-drop electric annunciator.

Referring to the drawing by numerals, 1 indicates an electric battery or other source of electric current, and 2 a bus bar which in practice is usually positioned on the annunciator case, there being a suitable connection 3 from one side of this battery to the bus bar. 25 4—5, 6—7, and 8—9, denote a series of groups or pairs of complementary electro-magnets, each pair comprising what I shall term a call magnet and a resetting magnet, the coils of these magnets being designated 30 respectively by 4^a, 5^a, 6^a, 7^a, 8^a, 9^a. Co-operating with these three pairs of electro-magnets are the three pivoted armatures 10, 11 and 12. One end of the coils 4^a, 6^a and 8^a of electro-magnets 4, 6 and 8 which form the 35 "call" magnets, are each connected at 14 to the bus bar 2 and through it to the battery 1, while the other ends of said coils are each connected by wires 15 to a series of three call buttons 16, 17 and 18, one for each of the call magnets. The contacts 19 for each 40 of these call buttons are all connected with wire 20 which in turn is connected to one terminal of the alarm 21. The other terminal of this alarm 21 is connected to the wire 22, one end of which connects with the opposite side of the battery from wire 3 and the other end of which wire 22 is connected to a reset button 23. A contact 24 for this reset button is provided, which contact is connect-

ed with a wire 25 provided with three 55 branches 26 each connecting respectively with one end of the coils 5^a, 7^a and 9^a of the electro-magnets 5, 7 and 9 forming the "resetting" magnets. The other ends of these coils are each connected to contacts 27 positioned to be engaged by contact buttons 28 carried by the armatures 10, 11 and 12. These armatures are each in turn electrically connected to the bus bar 2 by wires 33. Each of these armatures carries a slotted arm 29 within which rides a pin 30 carried by the lower end of an indicator arm 31 pivoted intermediate its ends. Each of these arms 31 carries at its upper end, an indicator disk 32 which is normally away from in front of 70 an indicator opening in the annunciator case (indicated in dotted lines in the drawing) and, when its call button is energized, is moved out in front of said opening to indicate that the room or person designated by 75 said opening, has called. I do not desire to be limited to any specific form of indicator arm but am merely showing one simple and effective form of indicator as illustrative of the application of the invention. 80

With the foregoing in mind, the operation of the annunciator circuits is as follows: Assuming that all signal arms are in normal position, as shown in the drawing by the signal arms 31 controlled 85 through the armatures 10 and 11, the circuit closer formed by the button 18 and contact 19 is actuated to close the circuit. Current then flows from the battery through connecting wire 3, bus bar 2, electro-magnet coil 8^a through its connection 90 14 with said bus bar, wire 15 to the contact 18, then through contact 19, wire 20, alarm 21, and wire 22 to the battery, thereby closing the circuit, sounding the alarm and energizing electro-magnet 8 to pull its armature 12 down to the position shown in the drawing, this movement of the armature, moving its signal disk 32 out in front of the opening in the annunciator. The mere 100 weight of this signal arm being thrown to the right, will, through its end 30 hold the armature 12 to the position shown until reset by the following means: When the armature 12 has been moved down to the position shown in the drawing, its contact button 28 engages its contact 27, these parts forming in effect a mechanically controlled 105

circuit closer for the reset magnet circuit. If it is desired to reset this armature 12 and restore the indicator disk to its non-indicating position, the reset button 23 is moved to close the circuit through contact 24. When this is done, the circuit closed is as follows: from the battery through wire 3, bus bar 2, connection 33 to armature 12, thence to contact button 28, through contact 27, electro-magnet coil 9^a, branch wire 26, wire 25, thence through contact 24, reset button 23, wire 22 and back to the battery. The closing of the circuit will therefore energize the electro-magnet 9 and pull its armature 12 down to contact with the core of electro-magnet 9 thereby throwing the indicator arm 31 and its disk 32 back to its normal non-indicating position as illustrated by the indicator arms controlled through armatures 10 and 11 in the drawing. The armature 12 will remain in this reset position until its controlling call button again closes the circuit in the manner described. It will be seen that the calling and resetting circuits overlap to some slight extent in that they use a common conductor for part of their respective circuits. This not only tends to simplicity in structure and in construction but is productive of substantial economies.

I have described the calling and resetting operation only of one pair of electro-magnets as the circuits in the case of all groups are similar and need no further specific description. It is important to note that when the reset button 23 is moved to close the resetting circuit or circuits, current will flow only through those reset magnets whose circuits have been closed by the attraction of their armatures to their call magnets. The current therefore will flow only through the coils of those magnets which must be energized to reset an indicator arm; consequently, a minimum of electric current is expended in the resetting operation.

While I have herein described a specific embodiment of my invention, I desire it understood that various modifications thereof are possible within the spirit of the invention and the scope of the appended claims.

What I claim is:—

1. In a device of the character described, in combination, a plurality of groups of electro-magnets, each group embodying a calling magnet and a reset magnet, an armature for each magnet group, an indicator movable into two tell-tale positions by the movements of its armature, a source of electric current, normally open electric circuits through said call magnets and current source, a call circuit closer for each call circuit adapted to close its certain circuit to energize the call magnet thereof, thereby attracting its armature and moving

its indicator into calling position, an interrupted resetting circuit through each reset magnet, means whereby the attraction of an armature to its call magnet closes a break in a resetting circuit to prepare it for operation, and a single resetting circuit closer in common to at least two resetting circuits and adapted to energize the reset magnets of only such resetting circuits as have been prepared for operation by the attraction of the armatures to the call magnets, to thereby attract the armatures thereof and reset their indicators.

2. In a device of the character described, in combination, a plurality of groups of electro-magnets, each group embodying a calling magnet and a reset magnet, an armature for each magnet group, an indicator movable into two tell-tale positions by the movements of its armature, a source of electric current, normally open electric circuits through said call magnets and current source, a call circuit closer for each call circuit adapted to close its certain circuit to energize the call magnet thereof, thereby attracting its armature and moving its indicator into calling position, an interrupted resetting circuit through each reset magnet, said call and reset circuits having a portion of their circuits overlapping by means of a conducting member in common thereto, means whereby the attraction of an armature to its call magnet closes a break in a resetting circuit to prepare it for operation, and a single resetting circuit closer in common to at least two resetting circuits and adapted to energize the reset magnets of only such resetting circuits as have been prepared for operation, to thereby attract the armatures thereof and reset their indicators.

3. In a device of the character described, in combination, a plurality of groups of electro-magnets, each group embodying a call magnet and a reset magnet, a pivoted armature for each magnet group, an indicator controlled by each armature having two tell-tale positions and moved from one to the other of said positions by the movement of its armature, a source of electric current, a bus bar, a connection between said current source and said bus bar, a connection between said bus bar and the call magnet of each group, a circuit closer for each call magnet in connection therewith and with said current source whereby each call magnet ~~may~~ be energized to attract its armature thereto and move its indicator, a connection between said bus bar and each armature, a resetting circuit closer, a connection between said resetting circuit closer and said current source, a connection between said resetting circuit closer and each reset magnet and its armature, closed only when said armature is moved by the

energizing of its call magnet, whereby, when said resetting circuit closer is operated, current flows only through such reset magnets whose connections have been closed by the movement of their armatures, and attracts said armatures thereto to move the indicators controlled thereby into their first position.

4. In a device of the character described, 10 in combination, a plurality of groups of electro-magnets, each group embodying a call magnet and a reset magnet, a pivoted armature for each magnet group, an indicator controlled by each armature having 15 two tell-tale positions and moved from one to the other of said positions by the movement of its armature, a source of electric current, a bus bar, a connection between said current source and said bus bar, a connection 20 between said bus bar and the call magnet of each group, a circuit closer for each call magnet in connection therewith and with said current source whereby each call magnet may be energized to attract its armature thereto and move its indicator, a connection between said bus bar and each armature, a resetting circuit closer, a connection between said resetting circuit closer and said current source, a connection 25 between each reset magnet and its armature closed by said armature when its armature is moved by the energizing of its call magnet whereby each resetting circuit is closed at one point only when its call magnet has been 30 energized, and whereby, when said resetting circuit closer is operated, current flows only through such reset magnets as have been so closed by the movement of their armatures, and attracts said armatures thereto to move 35 the indicators controlled thereby into their first position.

5. In a device of the character described, 40 a plurality of signal controlling armatures, a calling electro-magnet and a complemen- 45 tal resetting electro-magnet for controlling

each of said armatures, each calling magnet being arranged to shift its armature to signaling position and its complemental resetting magnet being arranged to shift said armature to a non-signaling position, a 50 source of electric current, a circuit therefrom having branches leading through each of the calling magnets, each branch including a manually operable circuit closer, another circuit from said current source, said 55 last mentioned circuit having interrupted branch circuits leading through the resetting magnets of each set, each of said branch circuits being closed by its respective armature through its call magnet, and a single 60 resetting circuit closer in common to at least two resetting branches of said resetting circuit.

6. In a device of the character described, 65 a plurality of signal controlling armatures, a calling electro-magnet and a complemen- 70 tal resetting electro-magnet for controlling each of said armatures, each calling magnet being arranged to shift its armature to signaling position and its complemental reset- 75 ting magnet being arranged to shift said armature to a non-signaling position, a source of electric current, a circuit therefrom having branches leading through each of the calling magnets, each branch includ- 80 ing a manually operable circuit closer, another circuit from said current source, said last mentioned circuit overlapping the first circuit in part and having interrupted branch circuits leading through the resetting magnets of each set, each of said branch circuits being closed by the movement of its 85 respective armature through its call magnet, and a single resetting circuit closer in common to at least two resetting branches of said resetting circuit.
